AUTOMATIC WINDOW CONTROL

Fred H. Rowe, Gloucester, Mass., assignor of one-tenth to William L. Hall and one-tenth to Augustus S. Nye, Boston, Mass.

Application December 16, 1933, Serial No. 702,701

2 Claims. (Cl. 16—200)

My present invention relates to automatic window control and more particularly to an automatic control for an automobile window.

Hitherto much difficulty has been experienced due to the present conventional arrangement for raising and lowering windows in automobiles. The mechanism as at present used often becomes stiff and at times almost impossible to operate especially in the case of the driver who may have only one hand available for the purpose. At best either raising or lowering the window can be done only slowly and requires much more attention and force than should be necessary.

With these difficulties in mind I have designed a new window for automobiles which obviates the above mentioned disadvantages and moreover has other very attractive features besides.

The principal object of my invention is therefore an improved window control for automobiles.

Another object is an automatic control which gives much greater flexibility and speed of operation.

Other objects and novel features comprising the construction and operation of my invention will appear as the description of the same progresses.

In the drawing illustrating the preferred embodiment of my invention

Fig. 1 is a side elevation of an automobile door having its exterior surface removed showing a sliding glass panel associated with spring members.

Fig. 2 is a cross section taken on the line 2—2 of Fig. 1, showing a cam control mechanism and

Fig. 3 is a cross section taken on the line 3—3 of Fig. 1 showing how the spring extremities are secured.

Referring more in detail to the drawing 10 indicates a window glass contained in a frame member 11 which is slidably disposed within a door casing 12. The window and frame 11 are adapted to be lowered or forced downward by means of the grip 13. Solidly attached to the bottom of the frame 11 are two supporting arm members 14 and 15 having their lower extremities converging and embedded in a circular block 16 suspended thereby. The block 16 is provided with a bolt 17 centrally located therethrough and projecting outwards. Rotatably mounted on the projecting portion of the bolt 17 and adjacent the block 16 are two disc members 18 and 19 which are lightly held together by means of the nut 20. Located through the peripheries of the disc members 18 and 19 are grooves 21 and 22.

Vertically disposed adjacent either inner side of the door casing 12 are two spring members 23 and 24 having central coil portions 25 and 26 and opposed end portions 27 and 28 diagonally extending upwards and passing through the grooves 22 and 21 respectively. Located adjacent the coil portion 25 and 26 is a second set of coiled springs 29 and 30 which encircle the upwardly extending portions 27 and 28 and are seated against washer members 31 and 32. The washer members 31 and 32 are adapted to bear against the discs 18 and 19 and to be compressed backward against the springs 29 and 30.

Internally mounted adjacent the right edge of the door casing 12 is a shaft 33 extending inwardly towards the window 10. Solidly mounted on the inner extremity of the shaft 33 is an offset cam 34. Somewhat centrally located on the shaft 33 is a lever member 35 solidly attached thereto and extending upward. Horizontally attached to the extremity of the lever 35 is a cross arm 36 having its end portion terminating in a button 37. Recessed against the lever 35 and encircling the shaft 33 is a coiled spring 38 adapted to be compressed inward when the lever 35 is pressed forward at right angles to it. The face of the cam 34 is so constructed that both release and brake control are possible by different adjustment of pressure on the button 37 which actuates the cam 34 from the shaft 33. The normal position of the button 35 is maintained outwardly by the coiled spring 38. When slight pressure is exerted upon the button 37, the normal braking action of the cam face against the window frame 11 is proportionately relieved, further pressure on the button results in an unimpeded sliding of the window as actuated by the spring and a final strong pressure on the button will cause the cam 34 to act as a positive brake again.

In operation assuming that the window is in a closed position to start with, it may be pulled downwards by the hand of the operator inserted in the grip 13. The cam is so designed that downward travel of the frame 11 will not be affected by it yet an upward return is positively prevented for any point to which it may be desired to lower the window to. As the frame slides down, the spring portions 27 and 28 advance through the grooves 22 and 21 respectively with the disc 19 adjusting itself in counter-clockwise rotation and the disc 18 in clockwise rotation. When it is desired to return the window to a closed position, it is only necessary to remove the braking action of the cam 34 and allow the coiled

springs 25 and 26 to elevate the window as controlled by the button 37.

While I have shown a particular form of spring motivation in connection with the double acting 5 cam, it is to be understood that various modifications may be resorted to in this connection while still continuing to adhere to the spirit of my invention.

Having thus described my invention what I 10 claim is:

1. In a door having a window frame slidably disposed therein and provided with a cam control mechanism engaging with the side of said window through said door, a closing mechanism comprising a bracket member centrally fixed to the lower edge of said window frame, a shaft member horizontally located through said bracket and provided with disc members rotatably mounted thereon and lever springs internally located 20 against the sides of said door with the lower extremities anchored to said door and further hav-

ing each of the upper ends slidably secured through one of the said disc members respectively.

2. In an automobile door having a window frame constructed therein and a window slidably disposed in said frame and further provided with a friction control mechanism engaging with said window through said frame, a lifting mechanism for said window comprising a bracket centrally fixed to the lower edge of said window having a block member suspended therefrom, a shaft member horizontally located through said block and having circular plates rotatably mounted thereon adjacent said block, said plate members provided with elongated slots through their peripheries, and lever springs having lower extremities anchored in said door and the upper extremities respectively engaging in a slidable manner through a said elongated slot of a circular plate.

FRED H. ROWE.
